ELECTRIC SWITCH

Application filed November 7, 1929. Serial No. 405,469.

The present invention relates to electric switches and more particularly to heavy duty switches equipped with fuses and arranged for safe fusing.

Among the objects of the invention is a switch in which the "live" parts are completely covered against accidental touching when the device is in its customary or intended use.

Another object is a switch in which the changing of fuses may be done without danger to the operator because of the complete covering of the "live" parts under either "open" or "closed" circuit conditions.

Another object is a simple interlock between the enclosure cover or housing and the switch, preventing opening of the former when the switch is "closed".

Still other objects will readily occur to those skilled in the art upon reference to the following description and the accompanying drawings, in which

Fig. 1 is a central vertical section of the preferred form of the switch.

Fig. 2 is a front elevation of the switch with the enclosure door removed.

In the drawings, the switch is indicated as comprising a plate or supporting platform 10 of insulating material near the near edge of which is a second plate 11 of insulating material fixed to the first plate and extending vertically. Upon this second plate are terminals 12 to which are secured the leads 13 extending up through the bottom of the device and being fixed by means of the bolts or screws 14. The upper ends of the terminals 12 each have secured thereto a switch blade 15 extending diagonally upward and backward so as to present the side of the blade toward the front of the switch.

In the form of switch shown, there will be three of the terminals 12 and switch blades 15 and a corresponding number of movable elements which are about to be described.

At the forward edge of the plate 10 are mounted a plurality of terminal members 20, in the present case, three, provided underneath the plate 10 with means for attachment of the wires or leads 21, these being the lines or leads running to the load side of the

switch. A convenient means of attachment of the leads 21 is shown as the socket portion 22 with a suitable screw 23. The members 22 are secured to the plate 10 and are provided with a forwardly projecting portion 24 extending beyond the front edge of the plate 10 or opposite slots therein so that the portion 25 of the member 20 may extend up above the plate 10. In each of the members 20 there are two of these vertically extending portions 25 which are provided near their upper ends with a hole for a bolt 26, and in each case the members 25 are spaced a suitable distance to receive between them a spring contact member 27 which is carried on the bolt 26 and adapted to rotate thereon. This spring contact member 27 consists of a metallic strip bent to U-form and with the sides bent inwardly and downwardly within the U so as to receive between these two ends or side pieces one of the blade ends of a heavy duty fuse 28 and form a hinged contact and a fuse slip.

The whole switch assembly is enclosed within a suitable enclosure or box 30 provided with a door 31 and hinged or pivoted on the sides of the box 30 is a bail member 32, the hinge pins being the bolt 33 and the spindle end 34 of a handle 35 which latter is mounted on the outside of the box with the spindle projecting through the wall and fixed to the bail 32. The several bolts 26 and 33 and the spindle 34 of the handle 35 are in alignment across the box.

Carried by bail 32 is a plate 40 of insulating material secured to the bail as by the screws 41. This plate, when in "closed" circuit position of the switch, extends from near the front of plate 10 diagonally upward towards the rear of the box and in "open" circuit position occupies a substantially vertical position, as indicated in dotted lines in Fig. 1. The upper edge of the plate 40 is provided with spring contact members 42, one for each of the blades 15, which contact members extend through the plate 40 and are adapted to contact on the rear side of the plate 40 with the blades 15 and on the front side of the plate with the blade 43 of a fuse 28.

In Fig. 1, the full line position shown is the "closed" circuit position, and the circuit being from a lead 13 up through the terminal 12 and blade 15 to contact member 42 and 5 down through the fuse of the spring member 27 and members 25 through terminal 20 to the lead 21.

In the form of the device shown, the door 31 of the enclosure is hinged at the top, as at 10 50, and near the top is provided with ears 51 to which are pivoted links 52, the other ends of which are pivoted to a substantially semi-circular cam or lock piece 53 which, in turn, is rotatably mounted on the side wall 15 of the enclosure, so that, when the door 31 is opened, the cam member 53 is rotated from the position shown in Fig. 1 substantially a half revolution. Cooperating with this cam member 53 is an extension 54 carried by the 20 plate 40, there being one of these cams at each side of the switch and one of the extensions 54 adapted to cooperate therewith. The cams 53 and extensions 54 are so located that, with the plate 40 in "open" circuit position, 25 only a very small movement of the door 31 brings the cam behind the extension and prevents closing of the switch. Further, movement of the cam and therefore the door 31 is prevented until the switch is fully open.

30 Further, the door 31 is also provided with an eye member 60 cooperating with a suitable hook 61 carried by the bail member 32 so that when the door is closed and the switch moved to closed position, the hook 35 enters the eye 60 and prevents opening the door unless the switch is in full open circuit position. When, however, the switch is in open circuit position and the door has been opened, the extensions 54 are prevented 40 by the cam 53 from moving backward and it is therefore impossible to close the switch when the door 31 is open.

The enclosure 30 is preferably also provided with a pair of stop members 65 located 45 on the sides of the enclosure and adapted to prevent the movement of the plate 40 too far forward when the switch is opened. In order to provide for installation and repairs or other proceedings within the enclosure, it 50 is preferred to attach the stop members 65 by means of removable screws 66 so that the plate 40 may be moved, if desired, to the position indicated at A in Figure 1, thus permitting access to the "live" terminals 12.

55 Now having described the invention and the preferred forms of embodiment thereof, it is to be understood that the said invention is to be limited not to the details herein set forth, but only by the scope of the claims 60 which follow.

Claims:

1. An electric switch comprising a fixed insulating support, a second insulating support hinged thereto, a "live" terminal carried by said fixed support, a pair of contact

members, one of which is connected to said terminal and the other of which is carried by said hinged support, upon the side adjacent said terminal, a fuse clip on the other side of said hinged support and connected 70 to said other member, a movable fuse clip in alignment with the hinges of said hinged support, means for electrically connecting said latter clip to a load line terminal, and means for swinging said hinged support and 75 a fuse carried thereby to "close" and "open" said pair of contact members, one end of the fuse and the hinged clip moving as a unit, without disengagement, the hinged clip always being in connection with the terminal 80 to which it is attached.

2. An electric switch comprising an enclosing housing having mounted therein near its lower end a horizontal insulating platform, a "live" terminal mounted at the rear 85 of said platform, a load terminal near the front of said platform and having an ear extending upwardly therefrom, an insulating plate hinged to said housing with its center of rotation in alignment with said ear, 90 fuse holding means hinged to said ear also in alignment with said center, a second fuse holding means near the free edge of said plate and extending to the under side thereof and provided with means for making 95 contact with said "live" terminal, and means outside of said enclosure for swinging said plate to make and break said contact.

3. An electric switch comprising a normally horizontally placed platform having at 100 its rear edge "live" terminals each comprising a contact blade, a movable plate hinged at the forward edge of said platform and carrying contact members adapted to coact with said blades, fuse holding elements connected to said contact members on the face of said plate away from said blades, co-operating fuse holding members on said plate and in alignment with the hinges thereof, 110 means for swinging said plate to an open circuit position, an enclosure for said switch having a door and means connected with said door to prevent said plate from swinging to closed circuit position when said door is open.

4. An electric switch comprising a normally horizontally placed platform having at 115 its rear edge "live" terminals each comprising a contact blade, a movable plate hinged at the forward edge of said platform and carrying contact members adapted to coact with said blades, fuse holding elements connected to said contact members on the face of said plate away from said blades, co-operating fuse holding members on said plate and in alignment with the hinges thereof, means for swinging said plate to an open circuit position, an enclosure for said switch having a door and means connected with said door to 120

125

130

135

145

prevent said plate from swinging to closed circuit position when said door is open.

5. In an electric switch comprising a fixed "live" contact member, a movable contact member adapted to coact therewith and carried by a hinged plate, an enclosure for said switch and a door therefor, a rotatable member carried by said housing, and means on said movable plate coacting therewith and 10 freely movable when said rotatable member is in one position but adapted to prevent the movement of said plate toward circuit closing position when said circuit closing member is in another position.

15 6. In an enclosed electric switch, a platform extending to the rear of the enclosure and having "live" contact members carried thereon, a plate of insulating material hinged at the forward edge of said platform and 20 normally extending upwardly in front of said members, fuses carried by said plate on the forward side thereof, means on the rear side of said plate for connecting said fuses in circuit when said plate is swung backward 25 and disconnecting said fuses from said circuit when said plate is swung forward, a stop for limiting the forward movement of said plate and means operated by the door of said enclosure for preventing the opening of the 30 latter when said plate is in any other position than against said stop.

7. In an enclosed electric switch having a hinged plate of insulating material carrying elements adapted to make and break the 35 circuit, a lateral extension on said plate extending to near the enclosure wall, a stop carried by said wall and adapted to limit the movement of said plate in circuit opening direction, a cam member carried by said wall 40 and adapted to be rotated when the door of said enclosure is opened, said cam cooperating with said extension to prevent movement of said plate when said door is open and means to prevent opening said door when 45 the plate is in circuit closing position.

8. In an electric switch, two spaced fixed contacts, a hinged insulating support, a contact on the rear wall of said support and adapted to engage one of said fixed contacts, 50 a fuse clip on the front wall of said support and connected to the contact on the rear wall thereof, and a second fuse clip hingedly connected to the other one of said fixed contacts and disposed in front of said support.
